US0D1004080S

(12) **United States Design Patent** (10) **Patent No.:** **US D1,004,080 S**
(45) **Date of Patent:** **** Nov. 7, 2023**

(54) **TAMPON**

(71) Applicant: **Kimberly-Clark Worldwide, Inc.,**
Neenah, WI (US)

(72) Inventors: **Bliss Elizabeth Cohen**, Appleton, WI
(US); **Steven Craig Gehling**, Oshkosh,
WI (US); **David Kevin Oldroyd**,
Greenville, WI (US)

(73) Assignee: **KIMBERLY-CLARK WORLDWIDE,**
INC., Neenah, WI (US)

(**) Term: **15 Years**

(21) Appl. No.: **29/651,248**

(22) Filed: **Oct. 2, 2018**

(57) **CLAIM**

The ornamental design for a tampon, as shown and described.

DESCRIPTION

FIG. 1 is a perspective view of an embodiment of a tampon;
FIG. 2 is a front view of the tampon of FIG. 1, wherein the
back view is identical to FIG. 2;

FIG. 3 is a top view of the tampon of FIG. 1; and,
FIG. 4 is a bottom view of the tampon of FIG. 1.
In the drawings, the evenly spaced broken lines represent
environment structure and form no part of the claimed
design.

1 Claim, 3 Drawing Sheets
